MEANS FOR SUPPORTING AND POSITIONING CORE BARS IN FLASKS, AND COMBINATIONS OF SUCH MEANS WITH CORE BARS AND FLASKS

James R. McWane, deceased, late of Birmingham, Ala., by Arthur T. McWane, William McWane, and Jelks H. Cabaniss, executors, Birmingham, Ala., assignors to McWane Cast Iron Pipe Co., Birmingham, Ala.

Application May 11, 1934, Serial No. 725,198

4 Claims. (Cl. 22—101)

This invention relates generally to means for supporting core bars in flasks and to combinations of such means with core bars and flasks. More particularly, the invention relates to means for supporting core bars in flasks in the production of pipes cast horizontally and to combinations of such means with horizontal core bars and flasks.

For many years it was considered impractical if not commercially impossible to cast pipes and similar cylindrical articles horizontally, i. e., with the axis of the mold and core disposed substantially in a horizontal plane. This was due principally to the fact that in prior attempts to cast such articles horizontally it was considered necessary to employ chaplets for holding the core "centered" with respect to the mold cavity, and these chaplets, being cast into the pipe or other article, resulted in the formation of leakage spaces between the stems of the chaplets and the metal cast around the stems. Chaplets were employed in order to prevent deflection of the core or core bar due to several different forces, viz.; the weight of the core or core bar, the substantially lateral pressure on the core exerted by the velocity pressure of the stream of metal entering the mold, the unequal expansion of the top and bottom portions of the core bar resulting from the bottom of the bar being heated before the top thereof during filling of the mold from the bottom up, and the upward vertical force due to the natural buoyancy of the core in the molten metal.

In Patent 1,702,657 and Reissue Patents 17,121, 35 17,362, and 17,363, all in the name of James R. McWane, there are disclosed means for supporting core bars in flasks for the production of horizontally cast pipe in such manner that the cores may be so positioned and held in the molds as to produce, without the use of chaplets, pipes or the like having an even thickness of metal. Many thousands of tons of pressure-tight pipe have been produced successfully by using the means disclosed in the patents referred to.

Generally stated, the core positioning means disclosed in the prior patents are constructed and arranged to exert upon the core bars a definite pressure capable of springing the core bars and giving them an initial deflection from a purely centered position. The direction and degree of the initial deflection is such that when a mold is poured the forces referred to above will just overcome the initial deflection of the core bar, moving the latter to centered position relative to the mold cavity so that the solidified

pipe or other casting will be of uniform thickness.

Inasmuch as forces act on the core bars both horizontally and vertically during pouring and solidification, it is necessary that the core bars be initially deflected both horizontally and vertically. The means disclosed in the prior patents referred to include pressure-producing elements which act in a direction inclined to both the horizontal and the vertical. In cases where the initial deflection of the core bar, say in a horizontal plane, is correct and the initial vertical deflection not correct, it has been found that actuation of the inclined pressure-producing elements for correcting the initial vertical deflection disturbs the horizontal deflection and thereby renders the complete initial deflection-setting of the core bar somewhat difficult.

An object of the present invention is to provide improved means for positioning and/or supporting a core bar in a horizontal mold adapted to exert initial deflection-producing pressures in a purely horizontal direction only. Another object is to provide a novel combination of such means with a flask and core bar. Further objects are to provide novel renewable bushings for supporting the core bars in horizontal molds, to provide a novel three point core bar support, to provide an improved form of yoke for association with a single core bar and having means for exerting purely downward pressure on the core bar, and to provide an improved device for exerting upward pressure on a core bar yet permitting the latter to expand and contract longitudinally without undue binding. Other objects will become apparent from a reading of the following description, the appended claims, and the accompanying drawings, in which:

Figure 1 is a top plan view of drag or bottom mold flask, core bars therein, and means arranged in accordance with the invention for positioning and supporting the core bars;

Figure 2 is a view in end elevation of the flask and associated parts shown in Figure 1, looking from the "bell" or left hand end as viewed in Figure 1;

Figure 3 is a sectional view taken on the line 3—3 of Figure 1;

Figure 4 is a fragmentary view in vertical section showing a replaceable core bar bushing support;

Figure 5 is a top plan view of the replaceable bushing;

Figure 6 is a top plan view similar to Figure 1 but showing the cope flask section in position on the drag;

Figure 12 is a view in side elevation of a yoke; and

15 Figure 13 is a perspective view of a core bar supporting block.

The invention is capable of embodiment in a number of different forms but for the purpose of illustration there is shown in the drawings a horizontally disposed mold flask A having drag 20 and cope sections 1 and 2 respectively and core bars B, B' coated with core sand and positioned in the flask as shown clearly in Figure 1. The coated core bars and the sand mold within the flask conjointly define mold cavities C and C' 25 respectively, these cavities including bell ends 3—3' and spigot ends 4—4', respectively. The drag flask section 1 (see particularly Figures 1, 2, and 3) comprises longitudinally extending sides connected by an end wall 5 adjacent the bell end 30 of the mold and an end wall 6 adjacent the spigot end thereof. Plates 7 and 8 extend across the drag flask section in planes spaced inward from the end walls 5 and 6.

35 The end wall 5 is formed with semicircular openings 9 and 9', the end wall 6 is provided with two similar openings 10, 10', the plate 7 is formed with two semicircular openings 11, 11', and the plate 8 is formed with two similar openings 12 and 12'. The openings 9, 10, 11, and 12 are in 40 line with the axis of the mold cavity C and are somewhat greater in diameter than the core bar B which extends through these openings. Similarly the openings 9', 10', 11' and 12' are in line 45 with the axis of the mold cavity C' and are of somewhat greater diameter than the core bar C' which extends through these openings.

50 For supporting and positioning the core bar B in the flask there are provided primary supporting means preferably comprising a replaceable semicircular bushing 13 positioned in the opening 11 in the plate 7 and a semicircular bushing 14 positioned in the opening 12 in the plate 8, the inner surfaces of these bushings serving as seats 55 for receiving the bell and spigot ends of the core bar B. The bushings may be secured in the flask by any suitable means but preferably by some means permitting them to be removed and replaced easily. Suitable means are shown in Figure 4 as comprising flat headed screws 15 extending through openings in the bushings and having threaded engagement with the flask, the heads of the screws being disposed in counter sunk portions of the bushing. It has been found that the primary core bar supports sometimes become 60 worn so that the core bar will not be accurately centered when placed in the flask. By providing replaceable bushings such as are described above, it is possible to correct any uncentered condition 65 of the core bar easily by merely removing a worn bushing and substituting another which has been machined or ground on its inner surface in a manner to produce the shifting of the core bar necessary to effect substantially perfect centering 70 thereof in the mold. The cost of maintaining the 75

core bars centered in this manner has been found to be considerably less than when following the old practice of remachining the flask itself or even providing a new plate 7 or 8.

For positioning the core bar longitudinally with 5 respect to the mold, the bell end of the core bar may be provided with a circumferential flange 16 the inner surface of which is adapted to abut against a lug 17 on the end wall 5 of the drag flask section. The lug 17 is of such length and the 10 flange 16 is so located on the core bar that when the two are in abutting relation as shown in Figure 1 the core will have the proper position longitudinally with respect to the mold.

15 It will be understood that the primary supports provided by the bushings 13 and 14 do not in themselves serve to effect any initial deflection of the core bar which, as stated above, is necessary in order to compensate for the deflection which occurs during pouring and solidification of 20 the metal. For effecting the necessary initial lateral deflection of the core bar means movable in a purely horizontal direction and preferably substantially in the plane of the flask joint and into engagement with the core bar on opposite sides 25 thereof are provided. In the illustrated embodiment of the invention this means includes a screw 18 extending through and having threaded connection with the lug 17 and a screw 19 having threaded connection with a lug 20, these screws 30 being located on opposite sides of the core bar B and lying in a horizontal plane substantially in the plane of the flask joint.

35 When preparing the mold and core assembly for pouring, the screws 18 and 19 are manipulated in a manner to effect deflection of the core bar in the direction necessary to compensate for the lateral pressure exerted by the molten metal entering the mold. For example, if the metal enters the mold cavity C from a point between the 40 cavity C and the cavity C', it will be necessary in preparing the mold and core assembly to initially deflect the core bar B inwardly with respect to the center of the drag flask section or in other words downwardly as viewed in Figure 1. 45 This deflection may be accomplished by turning the screw 18 in a direction to cause it to travel inwardly against the core bar B and by turning the screw 19 in a direction to cause it to move away from the core bar. If the metal is 50 introduced into the mold cavity on the opposite side thereof, the operation of the screws will be reversed, i. e., the screw 19 will be caused to exert pressure on the core bar and the screw 18 will be backed off. 55

It will be observed that manipulation of the screws 18 and 19 effects only the lateral deflection of the core bar and has no effect at all upon the vertical deflection thereof. Thus, if the correct initial vertical deflection has previously been 60 effected, operation of the screws 18 and 19 to produce the desired initial lateral deflection will not disturb the already correct initial vertical deflection.

The means for effecting the necessary initial 65 vertical deflection of the core bar B are separate from the means described above for effecting the lateral deflection and in the form shown in Figures 1 to 8, inclusive include a lug 21 projecting outwardly from the end wall 5 of the drag, a 70 screw 22 extending vertically through the lug and engaging the bottom of the core bar, a lug 23 extending outwardly from the end wall 6 of the drag and screw 24 extending vertically through the lug 23 and engaging the bottom of the core 75

bar. A bar 25 extends longitudinally and centrally of the drag section between the end wall 5 and the plate 7 and provides an anchorage for a vertically extending bolt 26 which passes 5 through a yoke 27 extending over and engaging the tops of the core bars B and B', a nut 28 having threaded connection with the bolt adapted to engage the top of the yoke 27 for forcing the latter downwardly to exert pressure upon the tops 10 of the core bars B and B'. There is further provided a bar 29 extending between the plate 3 and the end wall 6 of the flask and forming an anchorage for a vertically extending bolt 30 which passes up through a yoke 31 extending across and 15 engaging the tops of the core bars B and B', a nut 32 having threaded connection with the bolt 30 and being adapted to exert pressure upon the yoke 31 for causing the latter in turn to press down on the core bars. It will be apparent that 20 by manipulating the screws 22 and 24 and the nuts 28 and 32 the desired initial vertical deflection of the core bar B may be produced.

These means provide for deflecting the bar either upwardly or downwardly from its initial 25 position. Usually it is necessary to deflect the bar downwardly but in some cases the weight of the bar itself together with the sand on the bar causes too great an initial downward deflection and the bar has to be deflected upwardly.

30 The means for supporting, positioning and effecting initial deflection of the core bar B' are the same as those for supporting, positioning and initially deflecting the core bar B and therefore will not be described in detail. For convenience, 35 however, the positioning and initial deflection producing parts associated with the core bar B' are designated by the same reference characters as corresponding parts associated with the core bar B, with the exception that those associated 40 with the core bar B' are primed. Thus the lug 21' and screw 22' extending therethrough and engaging the bottom of the core bar B' are the same respectively as the lug 21 and the screw 22 passing therethrough for engagement with the 45 bottom of the core bar B, and so on.

A modified form of supporting, positioning and initial deflection producing means is shown in 50 Figures 9 to 13, inclusive. In the modification the primary supporting means includes a stationary pad 33 which may be integral with the plate 7 and located under and arranged to engage with the body of the core bar B and side set screws 34 and 35 having threaded connection 55 respectively with lugs 36 and 37 on the drag flask section, these screws being located on opposite sides of the core bar B and preferably lying substantially in the plane of the flask joint. An appreciable amount of clearance is provided 60 between the core bar and the opening 11 in the plate 7 of the drag so that the pad 33 and the screws 34 and 35 together constitute a three point primary support for the core bar. Wear on the pad 33 or the core bar may be corrected or compensated for by grinding the pad or by building 65 the pad up by welding and then grinding. Wear on the sides of the core bar or heads of the screws 34 and 35 can be compensated for by adjusting the positions of the screws in their associated lugs. Thus the three point support may be 70 maintained in proper condition or adjustment more economically than would be the case if the plate 7 supported the core bar B directly since in the latter case in order to compensate for wear it would be necessary either to replace the plate

or build up the entire inner surface of the opening 11 and then remachine the latter.

In the modification shown in Figures 9 to 13, inclusive, the initial lateral deflection producing screws 18 and 19 are the same as those described in connection with the form shown in Figures 1 to 8, but for exerting pressure on the bottom of the core bar there is provided a screw 38 having threaded connection with the lug 39 on the drag flask and having its head facing upwardly 10 under the core bar, and a block 40 interposed between the head of the screw and the bottom of the core bar. In the form shown this block is formed on its lower surface with a spherically shaped recess 41 adapted to fit over the rounded 15 head of the screw 38 so as to permit relative turning movement between the screw and the block. Preferably the upper face of the block 40 is provided with two parallel raised portions or pads 42—42 whose surfaces conform to the cylindrical outer surface of the core bar, these surfaces being adapted to engage the bottom of the core bar. The amount of force necessary to be exerted upon the bottom of the core bar for producing the required initial vertical deflection 20 thereof may be produced by turning the screw 38 in the lug 39. The block 40 will remain stationary relative to the core bar during such turning of the screw so that wearing of the core bar will be prevented. The pads 42—42 on the block 30 40 provide an extended seat for the core bar which permits longitudinal expansion of the latter when it is heated during pouring of the mold.

Figures 9 to 12 also disclose a modified form of yoke 43 which differs from the yokes 27 and 31 35 shown in Figure 1 essentially in that the yoke 43 is adapted to cooperate with only one core bar whereas the yokes 27 and 31 shown in Figure 1 necessarily cooperate with two core bars. In using the form of yoke shown in Figure 1 it is not 40 possible to change the downward pressure acting on one core bar without changing the downward pressure acting on the other so that in practice this arrangement sometimes makes it somewhat difficult to obtain the desired initial vertical deflection of both core bars. The yoke 43, however, 45 is adapted for cooperation with the flask and a single core bar only so as to avoid this difficulty. In the illustrated embodiment of the modification the yoke is of generally inverted U-shape 50 and is arranged to span the associated core bar B, the legs of the yoke being provided with hook shaped feet 44 and 45 adapted to engage under fixed parts 46 and 47 of the flask. A screw 48 passes through and has threaded connection with 55 the portion of the hook intermediate its legs and is adapted, when turned in the proper direction, to exert force downwardly upon the core bar. It will be understood that the initial vertical deflection of the core bar may be produced by manipulation of the screws 48 and 38 in a manner similar to the method of producing the initial vertical deflection of the core bar by means of the screws 22 and 24 and the nuts 28 and 32 shown in 60 Figure 1.

The embodiments shown herein by way of illustration have been found to be practical and are the at present preferred forms of the invention, but it will be understood that various changes may be made in the specific construction and relative arrangement of the parts without departing from the invention as defined in the claims.

What is claimed is:

1. In combination, a flask; a core bar therein; 75

a yoke spanning the core bar and having legs disposed on opposite sides of the core bar; means on said legs separately and operatively engaging relatively fixed flask parts on opposite sides of said core bar; and means having connection with the portion of the yoke between said legs and adapted to exert a clamping pressure on said core bar.

2. In combination, a flask; a core bar therein; a yoke spanning the core bar and having legs disposed on opposite sides of the core bar; hooked feet on said legs engaging under relatively fixed flask parts; and means having connection with the portion of the yoke between said legs and adapted to exert a clamping pressure on said core bar.

3. Means for positioning a horizontal core bar in a horizontal flask comprising screw means engaging the core bar and being mounted on a vertical axis and being movable in a purely vertical direction for exerting only vertical pressure on the core bar; and other screw means engaging

the core bar and being mounted on a horizontal axis and being movable in a purely horizontal direction for exerting pressure on the core bar in a horizontal direction only.

4. Means for supporting a core bar in a flask, the flask having a semi-circular opening for accommodating said core bar, said means comprising primary supporting means including a pad integral or fixed with respect to the flask and being located at the bottom of said semi-circular opening and being of relatively small circumferential extent as compared to the extent of said semi-circular opening; and side supporting elements on opposite sides of the core bar above said pad, said pad and said side supporting elements thereby providing a three-point support.
